(57) **CLAIM**

The ornamental design for an applicator head, as shown and described.

DESCRIPTION

FIG. 1 is a top perspective view of an applicator head embodying our design;
FIG. 2 is a bottom perspective view of the applicator head depicted in FIG. 1;
FIG. 3 is a front elevation view of the applicator head depicted in FIGS. 1 and 2;
FIG. 4 is a side elevation view of the applicator head depicted in FIGS. 1-3, with the opposite side elevation view being a mirror image thereof;
FIG. 5 is a rear elevation view of the applicator head shown in FIGS. 1-4;
FIG. 6 is a top elevation view of the applicator head shown in FIGS. 1-5;
FIG. 7 is a bottom elevation view of the applicator head depicted in FIGS. 1-6;
FIG. 8 is a perspective view of the applicator head similar to FIG. 1, but with the pivotal handle being swung to a different position;

FIG. 9 is a perspective view of the applicator head similar to FIG. 1, but with the material application pad being removed;
FIG. 10 is a bottom perspective view of the applicator head as depicted in FIG. 9;
FIG. 11 is a front elevation view of the applicator head as depicted in FIGS. 9 and 10;
FIG. 12 is a side elevation view of the applicator head as depicted in FIGS. 9-11, with the opposite side elevation view being a mirror image thereof;
FIG. 13 is a rear elevation view of the applicator head, as shown in FIGS. 9-12;
FIG. 14 is a top elevation view of the applicator head as shown in FIGS. 9-13; and,
FIG. 15 is a bottom elevation view of the applicator head as depicted in FIGS. 9-14.
The broken lines in the figures depict portions of the applicator that form no part of the claimed design.
